Primary Examiner — Cynthia Ramirez*Assistant Examiner* — Xavier Marti-Santos(74) Attorney, Agent, or Firm — Law Office of Scott C Harris, Inc(57) CLAIM

The ornamental design for a leaf shaped face patch, as shown and described.

DESCRIPTION

FIG. 1 shows a perspective view of a leaf shaped face patch showing my new design;

FIG. 2 shows a front perspective view of the leaf shaped face patch;

FIG. 3 shows a front view of the leaf shaped face patch;

FIG. 4 shows a first side view of the leaf shaped face patch;

FIG. 5 shows a top view of the leaf shaped face patch;

FIG. 6 shows a bottom view of the leaf shaped face patch; and,

FIG. 7 shows a perspective view of the leaf shaped face patch in condition of use.

The broken lines in the figures are for the purpose of illustrating environment, and form no part of the claimed design.
